UNITED STATES PATENT OFFICE.

FREDERICK GEORGE SCHRANZ, OF PHILADELPHIA, PENNSYLVANIA, ASSIGNOR TO SOUTHWARK FOUNDRY & MACHINE COMPANY, OF PHILADELPHIA, PENNSYLVANIA, A CORPORATION OF PENNSYLVANIA.

BENDING PRESS.

Application filed March 6, 1924. Serial No. 697,399.

- My invention is directed more particularly to that form of bending press in which the cooperating dies, or die and anvil, are mounted horizontally; one die, which may 5 constitute the anvil, occupying a fixed or substantially fixed position, and the other or shaping die being arranged for movement relatively to the same; in the present instance upwardly on the working stroke.
- 10 My present invention comprises a construction in which the anvil die is carried by a cross-head, which may be supported by a pair of columns at one end of the press and held in horizontal position against deflection which might be occasioned by the pressure of the shaping die when brought into contact with work to be operated upon by said dies, by links hinged to the base of the press; such links being suitably connected together at the top and operatively engaging the cross-head, and for this purpose they may be apertured to receive a cross-pin which may be arranged to overlie the end of said cross-head.
- 15 The pivotally mounted links may be swung away from their engagement with the cross-head to permit cylindrical work to be placed in operative position and removed, when corrugating boiler sections for instance, and for the removal of other kinds of work, and the operation of these links is under the control of a suitable piston mounted in a cylinder which may be arranged to swing on trunnions with respect to the press frame so as to be capable of effecting movement of said links in both directions.
- 20 These and other features of my invention are more fully described hereinafter; reference being had to the accompanying drawings, in which:
- 25 Figure 1, is a front elevation, partly in section, of a bending press embodying the features of my invention.
- 30 Fig. 2, is a plan view of the same.
- 35 Fig. 3, is an end elevation looking in the direction of the arrow α , Fig. 1.
- 40 Fig. 4 is a sectional elevation of the cylinder and piston employed for operating the pivoted links, and
- 45 Fig. 5, is a diagrammatic view illustrating the dies in operative position with respect to a sheet formed into a substantially rectangular shell.
- 50 In the drawings, 1 represents the base of my improved bending press, which may have 55 a pair of cylinders 2, each provided with a ram 3, suitably placed with respect to said cylinders; said rams being attached to a bed plate 4, to which the lower die or shaping member 5, is detachably connected. This die 60 or shaping member 5 is of a removable character in order that changes in dimension or form for different work operations may be made as desired, and the bed plate 4 may be grooved at 4^a to receive ribs 5^a carried by 65 dies or shaping members of the general type indicated at 5.
- 60 At one end of the base section, a pair of columns 6 are supported in any suitable manner, and a cross-head 7 is secured to the upper ends of these columns; the base of the press and said cross-head each being provided with outwardly projecting brackets, indicated at 8 and 9, respectively, with a tension or tie bolt 10 connecting said brackets whereby the cross-head may be held in a substantially horizontal and fixed position. The columns may be provided with stop collars or nuts 11, adjustable thereon, to determine the height at which said cross-head is supported, and the bolt 10 may be threaded to an extent to permit the desired adjustment, or bolts of different length may be employed. The cross-head 7 may carry a detachable anvil or die member of the type 70 indicated at 12, which may have a rib 12^a, 75 adapted to a groove 7^a, in said cross-head.
- 80 Disposed at the end of the press opposite the columns for the purpose of holding the cross-head 7 against deflection when pressure is applied upon movement of the lower die or shaping member 5 with respect to the anvil or upper die 12 connected to said cross-head, are a pair of links 15, having a 85 pivotal mounting comprising a pin 16, to which they are secured; such pin passing through the apertured end of a stem 17, which may be mounted in an apertured boss 18, carried by the base of the press and held in position by a collar or nut 19, at the 90 lower end of the same. This stem is adjustable so that if changes are made in the position of the cross-head with respect to the bed plate by raising or lowering the cross-head on the columns 6, corresponding 100 change can be made in the position of the links for proper engagement with said cross-head.
- 105

The links normally occupy the operative position shown by full lines in Figs. 1, 2 and 3, and they may be provided at their upper ends with a cross-pin 20, overlying the projecting end 7^b of the cross-head 7. The links are held against lateral displacement with respect to the cross-head when in operative position by means of a suitable pin 21, passing through the end 7^b of the 10 cross-head.

The links are movable upon their pivotal connection 16 to the position shown by dotted lines when it is desired to introduce cylindrical work into the press or to remove 15 other types of work operated upon, and such movement may be effected by providing the pivot pin 16, which is fixed to the links, with a forked crank 25, to which is connected a piston rod 26, having a piston 20 27, adapted to a cylinder 28; the latter being provided with trunnions 29, whereby it may swing in brackets 30, carried at the end of the press base. Such cylinder is connected with a suitable source of pressure 25 by a pipe 31 for the introduction of fluid to raise the piston and move the links into the position shown in Fig. 1, and for the exhaust of such fluid to lower the piston when it is desired to lower the links to 30 the position indicated by dotted lines. A suitable stop 32 may be provided upon which said links may rest when in the lowered position. The cylinder 24 is preferably set to one side at the end of the base, so that 35 the links may be raised and lowered without interference with their operating means.

In practice, after suitable dies or shaping members have been secured in place in the anvil and the movable bed plate, the work 40 to be acted upon, a metal sheet for instance, is introduced between the same, and pressure being supplied to the cylinders 2, the rams 3 will be lifted and with them the bed plate and lower die which will crowd the 45 work into the upper die, imparting to the plate the desired configuration. In Fig. 5, I have illustrated the bending of a sheet to form a square tank or shell, indicated at A. If a cylindrical object is to be operated 50 upon, the retaining pin 21 is removed and the links are lowered to the position shown by dotted lines by proper direction of pressure to the cylinder 28, or by their own weight when the cylinder is open to exhaust, and after the work to be operated 55 upon has been put in place, the links will be returned to operative position by admitting pressure to the cylinder 28 to raise the piston 27, and operation of the structure 60 may proceed as in connection with ordinary flat work; the links being lowered when cylindrical work or work such as illustrated in Fig. 5, is to be removed.

As will be understood, pressure may be 65 admitted to the cylinders 2 to move the

rams 3 upward, and exhausted from said cylinders to permit downward movement of the same, via a pipe 35, having separate connections 35^a and 35^b, leading to the respective cylinders; said pipe 35 being connected to a suitable source of fluid pressure. 70

I claim:

1. In a bending press, the combination of a base, a cylinder disposed therein, a ram adapted to said cylinder, a horizontally disposed movable bed plate connected to said ram, vertically disposed columns at one end of the press for guiding said bed plate, a horizontal cross-head carried by the upper ends of said columns, means for normally holding said cross-head in horizontal position, a link pivotally connected to the base opposite said columns with its upper end in operative engagement with said cross-head whereby the latter is held against deflection when the work is brought into contact therewith by the movable bed plate, and fluid-operated means for raising and lowering said link into and out of operative engagement with the cross-head. 90

2. In a bending press, the combination of a base, a cylinder disposed therein, a ram adapted to said cylinder, a horizontally disposed movable bed plate connected to said ram, columns at one end of the press for guiding said bed plate, a horizontal cross-head carried by the upper ends of said columns; said cross-head having aligned end extensions, means connected to one of said extensions for maintaining the cross-head in horizontal position, links pivotally connected to the base opposite said columns, a cross-pin carried by said links and overlying the opposite end extension of said cross-head whereby the latter is held against deflection when the work is brought into contact therewith by the movable bed plate, and means for raising and lowering said links. 95

3. In a bending press, the combination of a base, a cylinder disposed therein, a ram adapted to said cylinder, a horizontally disposed movable bed plate connected to said ram, a die member detachably secured to said bed plate, columns at one end of the press for guiding said bed plate, a horizontal cross-head carried by the upper ends of said columns; said cross-head having aligned end extensions and an anvil or die member detachably connected to said cross-head for cooperation with the die member carried by the bed plate; the latter having aligned end extensions underlying those of the cross-head; outwardly projecting brackets carried by the base and cross-head, a tension bar connected to the end extensions of the cross-head and base at one end of the structure, links pivotally connected to the base extension opposite said columns and in operative engagement with the extension of said 110

cross-head whereby the latter is held against deflection when the work is brought into contact therewith by the movable bed plate, and means for raising and lowering said

5 links.

4. In a bending press, the combination of a horizontally disposed base, a cylinder disposed therein, a ram adapted to said cylinder, a vertically movable bed plate connected to said ram, a die member detachably secured to said bed plate, columns at 10 one end of the press for guiding said bed plate, a cross-head carried by the upper ends of said columns, an anvil or die member detachably connected to said cross-head for 15 cooperation with the die member carried by the die plate, aligned extensions projecting from the base and cross-head, a tension bar disposed between and connecting the base and 20 cross-head extensions at one end of the structure, links pivotally connected to the base extension opposite said columns, a cross-pin carried by said links and overlying the end extension of said cross-head 25 whereby the latter is held against deflection

when the work is brought into contact with the die carried thereby by the movable bed plate, and fluid-operated means for moving said links into and out of cooperative relation with respect to said cross-head. 30

5. In a structure such as set forth in claim 1, a crank arm operatively connected to the link in fixed relation therewith, a cylinder operatively connected to the aligned extension of the base, a piston in said cylinder 35 connected to said crank arm, and means for directing pressure to said cylinder to raise and lower said link.

6. In a structure such as set forth in claim 1, a crank arm connected to the pivot pin 40 for the link, a swinging cylinder carried by the end extension of the press base, a piston in said cylinder connected to said crank arm, and means for directing pressure to said cylinder whereby the piston may be operated to 45 raise and lower said link.

In witness whereof I have signed this specification.

F. G. SCHRANZ.
